PROPELLER

Pierino Di Cesare, Chicago, Ill.

Application April 27, 1933, Serial No. 668,181

16 Claims. (Cl. 170—172)

The invention relates to propellers and more in particular to a novel propeller construction adapted for use in air craft or for marine purposes. The present application is a continuation in part of my copending application Serial No. 623,249, filed July 18, 1932, and abandoned August 9, 1933.

Among the objects of the present invention is to provide a novel construction of propeller for air craft and marine purposes which is of greater efficiency than those now being constructed and employed. In the present embodiment such increased efficiency is obtained without increasing the size or dimensions of the propeller and without adding any weight thereto, both of which are highly important factors in the design and construction of air and marine propellers.

A further object is to provide a novel construction of air or marine propeller provided with a central portion having a reduced passage or opening for receiving, guiding and ejecting the fluid acted on by the propeller for propelling an airplane, vessel or other object, through the medium or fluid in which it is operating, whereby to increase the efficiency of the propeller over the prior forms of propellers of the same size, weight or material.

Another object of the invention is the provision of a propeller for airplanes provided with a novel construction of hub and central portion adding to the efficiency of the propeller. In the various forms of prior constructions the central portion around the hub serves no useful purpose and in fact creates a vacuum which naturally has to be refilled with air. This vacuum tends to create a tremendous drag which has to be overcome by the power of the engine. It has been quite commonly accepted that the vacuum created by the inefficient central portion of the propeller was of little importance and it has often been cited that this created vacuum was of actual flying aid as the engine and fuselage following filled in this vacuum, but actual flying tests with such prior forms of propellers and the present novel propeller construction have proven that such is not the fact. By means of the present invention, this disadvantage has been eliminated and the space behind the central portion of the propeller is filled with air that is scooped up or collected by the contour of the propeller and exhausted or ejected into the trailing vacuum which is created as the aircraft is driven forwardly.

A further object of the invention is to provide a novel propeller construction formed with a longitudinally extending passage, throat or open-

ing adapted to collect the approaching air and exhaust or eject the same rearwardly of the propeller into the trailing vacuum created behind the propeller. This exhausted air forms a cooling medium adapted to cool the engine. 5

Still another object of the invention is the provision of a novel propeller in which the leading edge cuts the air sharply substantially to the center of the propeller, thereby greatly increasing the efficiency and effective operative length 10 thereof over prior propellers and those which are at the present time, standard equipment.

In such prior forms, a substantial part of the propeller's length constitutes the central portion which effects a drag and at best has no operative 15 or advantageous effect in propelling the airplane. In the present novel design, substantially the entire propeller length is effective in propelling the craft through the air.

Still another and further object of the invention is the provision of a propeller that is substantially vibrationless in operation. In the present embodiment, this is accomplished by scooping up and passing the air through the hollow central portion of the propeller which functions to 25 balance and stabilize the same. This portion guides the scooped air and steadies the operation.

Numerous actual flying tests of the present propeller have been made and these tests have shown that aircraft equipped with this type of 30 propeller show a better response to the controls. They also show a greatly increased performance and steady pull in climbing and the tests disclose that an airplane equipped with the present propeller will take off or rise at a much less distance 35 or in a smaller space than similar planes equipped with the prior or standard types of propellers. Flying tests at full throttle, and static thrust show a marked increase in efficiency and speed, while stalling tests disclose that the engine speed 40 must be greatly decreased or cut down before the plane will come to a stall. These tests also show that the present type of propeller minimizes the danger of a tail spin since there is a more direct flow of air or air stream which flows rearwardly along the fuselage and stabilizes the plane. All of these tests have been performed on similar planes using both a standard or prior commercial type of propeller and a propeller as disclosed in the present application. 45 50

The invention further consists in, and an object thereof is to provide a novel type of adjustable hub construction or central portion for a propeller of the present design or embodiment, in which the propeller hub and the central sec- 55

tion of the propeller is made adjustable and the dimensions of the passage, throat or opening adjacent the hub are varied, depending on the load or thrust imposed on the propeller. This construction permits the utilization of the same propeller for motors of varying sizes or horse power.

Another object is to provide a novel sectional hub construction in which the sections are automatically adjusted whereby to scoop or collect varying amounts of air in the passages or pockets provided therefor and to eject such collected air laterally or rearwardly of the propeller.

A still further object of the invention is the provision of a propeller of this novel type provided with one or more longitudinally extending passages, throats or openings and which is admirably adapted for marine use. Although the shape or contour of the blades of a propeller for marine use may vary somewhat over those for airplanes or other use, the principle involved and the function thereof is the same as in propelling an airplane, even though it is operating in water. Increased efficiency is secured by the use of this propeller over those now in standard use whereby greater propulsion, speed and power is secured.

Further objects are to provide a construction of maximum simplicity, efficiency, economy, and operation, and such further objects, advantages and capabilities as will later more fully appear, and as are inherently possessed thereby.

The invention further resides in the combination, construction and arrangements of parts illustrated in the accompanying drawings, and while there is shown therein a preferred embodiment, it is to be understood that the same is susceptible of modification and change, and comprehends other details, arrangements of parts, features and constructions, without departing from the spirit of the invention.

40 In the drawings:

Fig. 1 is a view in rear elevation of the propeller construction;

Fig. 2 is a view in side elevation thereof;

Fig. 3 is a view in front elevation of the propeller;

Fig. 4 is a fragmentary view in perspective with the propeller section taken in a plane represented by the lines 4—4 of Fig. 1;

Fig. 5 is a fragmentary view in vertical cross section taken in a plane represented by the line 5—5 of Fig. 1;

Fig. 6 is a fragmentary view in perspective of the central portion of the propeller;

Fig. 7 is a view in vertical cross section through a modified form of propeller in which the central section thereof is made adjustable;

Fig. 8 is a fragmentary view in vertical cross section taken through the hub and central section of the construction similar to that shown in Fig. 7, but showing the position of the telescoping members of the propeller when there is little or no load imposed thereon.

Fig. 9 is a view in vertical cross section through the adjustable central section and hub taken in a plane represented by the line 9—9 of Fig. 7;

Fig. 10 is a fragmentary view in rear elevation of the adjustable hub and central section;

Fig. 11 is a fragmentary view in perspective of the adjustable construction;

70 Figs. 12 and 13 are slightly modified forms of telescoping sections;

Fig. 14 is a view in rear elevation of a marine propeller;

Fig. 15 is a view in side elevation of a marine propeller;

Fig. 16 is a view in perspective thereof;

Fig. 17 is a view in vertical cross section taken in a plane represented by the line 17—17 of Fig. 14; and

Fig. 18 is a fragmentary view in vertical cross section of an alternate form of marine propeller in which the hub is positioned exterior of the body of the propeller.

Referring more particularly to the drawings and specifically to the disclosure in Figs. 1 to 6 of the drawings, the embodiment selected to illustrate the invention in these figures comprises propeller 1 having outwardly or oppositely extending blades 2 formed with a leading or cutting edge 3. This propeller may be employed to propel an airplane or other aircraft by either pulling or pushing it through the air. In the prior designs of propellers and those which are now standard or commercial equipment for airships or other aircraft, a great part, and in most instances substantially thirty-five percent of the propeller length comprises the central section which is at best ineffective and has no useful function in propelling the aircraft through the air.

In the present embodiment, this leading edge 25 3 and the effective operative portion of each blade extends for substantially the full length of the blade so that the effective surface area thereof is greatly increased.

As clearly disclosed in Figs. 1 to 6 inclusive, the blades are dished adjacent the central portion and this dished portion or depression 4 communicates with a passage, throat or opening 5 intermediate the outer plate 2^a carrying the blades and the inner plate 6 adjacent the hub 6^a of the propeller. This dished portion or depression forms a pocket for collecting the air acted on by the propeller blade and directs the air into the reduced passage or throat 5 from where it is exhausted or ejected laterally or rearwardly of the propeller. This form of construction not only gives greater surface area or effective operative surface of the propeller blade for acting upon the air or fluid in which it is operated, but collecting and scooping up of the air and the passage thereof through the passages 5 gives greater efficiency and propulsion to the propeller. This ejection of the air laterally and rearwardly of the propeller eliminates any possibility of forming a vacuum behind the central part of the propeller. It further stabilizes the operation of the propeller whereby to reduce or eliminate vibration thereof, and the stream of air passing rearwardly toward and along the fuselage of the airplane tends to stabilize the same in its travel.

The construction of the propeller may comprise an integral member or it may consist of sections as shown in Figs. 7 to 13 inclusive. In this construction, the blades 7 are made similar in contour to those shown in Figs. 1 to 6 inclusive, and each blade is provided with a dished portion or depression 8 adjacent the hub for collecting the air and directing it through the passage 9 from where it is ejected or exhausted laterally or rearwardly.

Each passage or throat 9 is made adjustable, the size thereof depending upon the load or thrust of the propeller. In Fig. 8 there is disclosed the position of the adjustable section when little or no load is imposed upon the propeller, while in Fig. 7 the parts are disclosed when there is a full load, in which case the passage or throat is reduced in cross section.

In order to permit an adjustment of the passages 9, the propeller is made sectional, the for-

ward or outer section 10 carrying the blades 7 and is slidable or movable longitudinally of the drive or propeller shaft 11. The rear section 12 is mounted stationary on the drive shaft and is provided with an upper and lower forwardly extending flange 13 adapted to receive therein or therebetween the rearwardly extending flanges 14 of the front section 10. Thus these members telescope together and are adapted to form therebetween the adjustable passages or throats 9 for the passage of and ejection of the air acted on and collected by the blades and which air is guided therethrough by reason of the depression or dished portion 8 adjacent the hub. The hub construction is likewise made sectional and comprises a quill or inner stationary hub part 15 mounted on the propeller or drive shaft 11 by means of a key 16. This stationary hub 15 at its forward end abuts against a collar or stop member 17 which is threaded onto the shaft. A washer 18 and a nut 19 are adapted to secure this collar or stop in position and prevent it from backing off of the threaded end of the propeller shaft. The stationary hub part 15 is splined, being formed with ribs 20 having grooves 21 therebetween. These grooves 21 are adapted to receive ribs or flutes 22 and the ribs or flutes 20 are adapted to be received in channels 23 in a slidably or movable hub member 24 which is adapted to encompass and slide on the inner stationary hub 15.

Thus the inner and outer hub members 15 and 24 respectively, provide a splined construction in which the members are provided with complementary surfaces so co-related and coacting to permit relatively free sliding movement therebetween. If desired, coacting faces between the complementary members may be provided with races adapted to receive bearings 25. The outer hub member 24 is provided with an annular flange 26 adapted to be connected to the front plate 10 by means of bolts or other suitable retaining means 27. A rear hub plate 28 is mounted on the reduced end 29 of the inner hub member 15 and is suitably connected to the inner plate 12 by bolts or other retaining means 30. A retaining or lock nut 31 is adapted to be threaded onto this reduced end 29 and to lock the hub plate 28 and plate 12 stationary upon the drive or propeller shaft 11.

Mounted within the passages or throats 9 is a coil spring 32 adapted to bear against the inner faces of the plates 10 and 12 and exerting a compression against the plate 10 tending to force this plate and the blades formed thereon or carried thereby, outwardly, as disclosed in Figure 8, the pressure of the air against the propeller overcoming whatever screw action there might be present to force the section 10 outwardly. When the propeller is operated under load, the plate 10 is forced inwardly and the spring 32 takes this rearward thrust. Since this spring 32 is mounted within the passages 9 and the air which passes therethrough, this spring is provided with a leather or other flexible covering 33. A spring 34 mounted on this covering is adapted to keep the covering expanded against the opposite side walls so as to at all times cover the springs against the entrance of dirt or other foreign matter.

As the spring 32 is of considerable compression and tends to force the plate 10 and the movable hub 24 outwardly, the invention comprehends the provision of a spring 35 seating against the annular flange 26 and an annular flange 36 formed

as a shock absorber so as to prevent the spring 32 from forcing the plate 10 outwardly with too great a force, thus preventing danger of the movable hub member 24 from striking against the collar 17 when the load is removed from the propeller. A cover or housing 37 is adapted to enclose the nose or front portion of the hub so as to prevent the entrance of water, ice, dust and other foreign matter. This nose, housing or cover is detachably secured to the annular flange 26 by bolts or other suitable retaining means 38. From the above disclosure, it will be readily seen that by varying the strength or compression of the spring 32, the same propeller may be utilized for engines of various sizes or horse power. It will also be clearly evident that the diameter and pitch of the propeller remain constant even though the sections or plates 10 and 12 forming the propeller are shiftable or movable relative to each other.

In Figs. 12 and 13 are disclosed modifications of the telescopic plates. In Fig. 12 the outer plate 10^a is provided with upper and lower flanges 39 adapted to receive the flanges 40 of the inner plate 12^a. This construction is similar to that shown in Figs. 7 and 8, with the exception that the flanges of the outer plates are exterior of and adapted to receive the flanges on the inner plate, rather than the reverse construction as disclosed in the prior figures.

In Fig. 13 the outer plate is similar in construction to that disclosed in Fig. 12, while the inner plate 41 is devoid of upper and lower flanges. In this construction the plate itself is received within the flanges 39 of the outer plate 10^a and which flanges are adapted to slide or move thereover.

In Figs. 14 to 18 inclusive, there is disclosed a propeller quite similar in operation and function as the propeller disclosed in Figs. 1 to 6 inclusive, but in which the contour has been altered in order to adapt it for marine purposes. Since this propeller functions to push a boat or other vessel through the water or medium in which it is operating, the mounting thereof is reversed from that of the airplane propeller in which the rear plate 6 faces the front of the fuselage. Were this type of propeller used in pushing a plane through the air, the plate 6 would necessarily face in a reverse direction so as to push rather than pull the airplane through the atmosphere. In the marine type of propeller, the rear plate 42 extends or faces away from the boat. This marine propeller is shown as provided with a pair of blades 44 provided with a leading edge 45. Throughout a substantial portion of the length of these blades, they are dished or concaved as at 46 whereby to scoop up the water or fluid being acted upon and direct and project this fluid through a throat or passage 47 extending adjacent the hub 48 of the propeller. The water or fluid passing through the throat or passage 47 impinges against the side walls 49 thereof, and helps to rotate the propeller. The water which is discharged or ejected from the throat 47 will pass laterally therefrom in a manner similar to that of the ejected air in the preceding disclosures, due to the constructions, contour and rotation of the blades and throat and the direction of travel of the vessel or structure being propelled.

This ejection adds greater efficiency and pushing power to the propeller, whereby the speed at which the motor is turning over may be reduced, or a smaller motor may be provided to accomplish the same power and speed as a larger motor employing the prior and standard types of

propellers. The discharge or ejection of the water or fluid gives added hydraulic propulsion.

In Fig. 18 there is disclosed an alternate form of marine propeller in which no interior hub is provided but the hub is exterior of the propeller and comprises an outer boss or hub member 50 and an inner boss or hub member 51 suitably keyed to the shaft 52. A lock nut 53 retains the propeller in adjusted position. It is of course to be understood that the propeller shaft 52 need not pass through the body of the propeller but a bearing member or hub may be provided exterior thereof on one of the plates, whereby leaving unobstructed the passage through the propeller.

With the clockwise rotation of the propeller as shown in Figure 1, the fluid will enter both throats or openings 5 in opposite directions, both towards the center. Due to the direction of rotation, the fluid of the right hand throat will be compressed against the upper right portion thereof, while a partial vacuum or void will exist in the upper left portion at the point of application of the dotted line from 5; the opposite conditions prevailing as to the lower portion of the throat. Thus it will be seen that the fluid will pass through the throat in opposite directions but on opposite sides of the shaft and interference between the two oppositely flowing currents will be avoided to a large extent. The same conditions and operation are found in the adjustable and marine propellers.

Although a greater efficiency is secured by the use of my propeller, the voyage is smoother since the agitation of the water is greatly minimized and the wake and swell following a vessel equipped with the novel propeller is noticeably decreased.

When the novel propeller is used on an airplane or for propelling air, the construction and design is such that in scooping or collecting the air and discharging or ejecting it from the longitudinal central portion of the propeller, the noise or metallic sound emitted is greatly minimized. This sound is generally caused by the broad surfaces of the blades striking the air and thereby causing vibration which is transmitted to the tip of the blades and thence to the atmosphere. In the present construction such broad surfaces are not present.

From the above description and the disclosure in the drawings, it will be readily seen that the invention comprehends a unique or novel form of propeller in which the design, contour and construction thereof greatly increases the efficiency over prior types of propellers. Thus, without increasing the size or weight of the propeller and in fact reducing the weight thereof, because it requires less material, this invention permits a decrease in the size of power plant or an increase in the power and speed with the same power plant.

Although I have disclosed the propeller as particularly adapted for propelling aircraft or boats, it is to be understood that it is equally as well adapted to propel any other structure in which a propeller may be employed, or for propelling currents of air or other fluid.

Having thus disclosed the invention, I claim:

1. A propeller provided with propelling blades and a central portion having a hub for connecting the propeller to the drive shaft, and telescoping sections at said central part adapted to be adjusted relative to each other and so constructed and arranged as to provide an adjustable outlet from the effective sides of said blades

for directing and ejecting fluid collected therefrom.

2. A sectional propeller construction adapted to be mounted on a drive shaft and rotatable therewith, comprising a plate fixed on said drive shaft and a plate slidably longitudinally thereon, said slidable plate carrying the propelling blades.

3. A propeller construction adapted to be mounted on a drive shaft, comprising a pair of members rotatable with said drive shaft but movable relative to one another and longitudinally of said shaft, one of said members carrying the propelling blades and said members being spaced apart to form a fluid passage therebetween.

4. A propeller construction adapted to be mounted on a drive shaft and rotatable therewith comprising a sectional central part including telescopic members providing a fluid passage therebetween and adapted to be adjusted relative to one another and longitudinally of said shaft and such adjustment depending upon the load imposed on the propeller, and compression means acting to force apart and separate said members.

5. A propeller construction adapted to be mounted on a drive shaft and rotatable therewith comprising propelling blades, an adjustable central section provided with telescopic parts providing a passage therebetween through which fluid acted on by said blades is directed and ejected, said passage being automatically adjusted by the load imposed on the propeller.

6. A propeller construction adapted to be mounted on a drive shaft and rotatable therewith comprising propelling blades, an adjustable central section provided with telescopic parts providing a passage therebetween through which fluid acted on by said blades is directed and ejected, said passage being automatically adjusted by the load imposed on the propeller, and compression means tending to extend and separate said parts.

7. A propeller construction adapted to be mounted on a drive shaft and rotatable therewith comprising propelling blades, an adjustable section centrally of said propeller and provided with parts adapted to be automatically adjusted to provide a passage therebetween of varying cross section depending on the load, means acting against the load tending to separate said parts and increase said cross section, and means acting to absorb any shocks to said parts resulting from a sudden decrease or removal of the load on the propeller.

8. A power-driven propeller for aircraft and marine use provided with outwardly extending blades, a member spaced from said blades and a passage intermediate said blades formed by said blades and member for receiving the fluid being acted on by the body of said blades and said passage communicating with the rear face of each blade, the rear face of said blades being so constructed and arranged as to collect fluid acted thereon and directing it toward the passage, said passage receiving and ejecting said fluid away from the blades.

9. A power-driven propeller provided with blades adapted to act upon the fluid in which it is operating, a plate spaced from said blades, and a tapered passage formed by said blades and plate and located centrally of said blades and communicating with the rear face of each blade for axially directing and discharging from the propeller the fluid being acted upon and collected by the blades.

10. A power driven propeller provided with

- spaced plates, one of which forms the propelling blades, a hub therefor, and a passage intermediate said plates and communicating with the rear face of said blades, said blades being so constructed and arranged that fluid acted upon and collected by said rear face is directed inwardly from the ends of the blades and toward the hub and ejected through said passage for the purposes set forth.
- 10 11. A power-driven propeller for aircraft and marine use provided with oppositely extending blades and a plate spaced from said blades, a hub therefor, and a tapered passage formed by said blades and plate on opposite sides of the hub and communicating with the rear face of each blade, said passage forming an outlet adjacent the hub for the fluid collected by the rear faces of said blades and directing and ejecting said collected fluid therethrough.
- 15 12. A power driven propeller for aircraft and marine use provided with oppositely extending blades and a member spaced from said blades, a hub therefor, and a tapered passage formed by said blades and member at the rear face of said propeller and extending on the opposite sides of said hub and longitudinally of the blades, the rear face of said blades being so formed as to collect and direct the fluid acted upon, inwardly from the ends thereof to the hub and through 20 said passage into the space behind the propeller.
- 25 13. A propeller for use on airplanes provided with a hub adapted to receive the drive shaft and blades extending outwardly therefrom for propelling the airplane through the air, the central portion of said propeller connecting said blades being provided with a member spaced from the blades and forming an opening communicating with the rear faces of said blades and adapted to collect the air acted on by the rear 25 faces of said blades and direct it inwardly toward
- the hub and through said opening and then rearwardly into the space directly behind said propeller.
14. An airplane propeller provided with a central part adapted to be connected to the drive shaft, blades extending outwardly from said central part for propelling the airplane through the air, said blades having their rear face dished to scoop and collect the air adjacent thereto and said central part being provided with a member spaced from the blades and defining a passage therebetween, the air collected by said dished blades being directed inwardly to said passage and ejected therethrough and rearwardly therefrom into the space behind the central part to 15 eliminate any tendency of the propeller to form a vacuum in said space.
15. An airplane propeller provided with a central part having a hub for connecting it to the drive shaft, blades extending outwardly from said central part and adapted to propel the airplane through the air, a plate spaced rearwardly of said blades, said part being provided with a tapered opening formed intermediate said blades and plate and communicating with the blades, 20 said blades being dished adjacent said opening to collect the air and direct said collected air inwardly towards the central part and through the opening and eject it into the space behind the central part of the propeller so as to fill said 25 space with the collected air and prevent the formation of a vacuum thereat.
16. A propeller comprising outwardly extending blades adapted to act upon the fluid in which the propeller is operating, and an adjustable hub 30 construction therefor including telescopic members adapted to form a passage therebetween to receive fluid acted on by the blades and to direct said fluid rearwardly of the propeller.

PIERINO DI CESARE. 40
